BARREL WITH COOLING MEANS FOR BEVERAGES

Frank S. Walker, Framingham, Mass.

Application February 27, 1948, Serial No. 11,690

2 Claims. (Cl. 225—40)

1

This invention relates to improvements in a barrel with cooling means for beverages. More especially it has to do with improved means for cooling the beverage in a barrel and still more particularly while the beverage is being withdrawn from the barrel.

In the dispensing of beverages such as charged liquids like ginger ale, soda water, or the various cola drinks for examples, it has heretofore been deemed necessary to keep the beverage in tightly sealed bottles from the time it is carbonated until it is to be drunk. The relatively small amount of fluid contained in the usual size of bottle is not sufficiently affected by temperature changes to be noticeable, but the transportation or storage of such charged liquids in the ordinary barrel or keg has not been practiced because such a quantity of the beverage at ordinary temperatures would soon lose its carbonation and become undrinkable. Even beer, and ale or the like, which is sold in kegs or barrels, should be kept below a certain temperature to insure that fermentation does not occur. Heretofore various insulated barrels have been proposed and have been used for beer and ale, but merely insulating a barrel is not enough. There must also be provision for insuring that as the liquid is drawn from the barrel it shall be at the lowest practicable temperature so that when discharged from an open faucet it will retain its liquid state and not become foamy or frothy or escape as gas.

The principal object of the present invention is to provide an improved barrel or keg which will have a flow passage through which a cooling fluid can be circulated continuously (except possibly during the relatively short period when the barrel is being transported on a truck or delivery wagon) and a separate passage for the beverage in thermal relation to the cooling fluid passage, the beverage flowing in a direction counter to that of the cooling fluid which may be either a gas or a liquid. In other words, the primary object of the invention is to provide a built-in delivery pipe within the barrel so arranged that the beverage will enter this pipe near the bottom of the barrel, travel along a generally helical path in thermal exchange relation to a counter-flowing cooling fluid, and thereby receive its maximum chill during such travel just prior to being dispensed.

The best modes in which I have contemplated

5

applying the principles of my invention are disclosed in the accompanying drawings but these are to be deemed illustrative for it is intended that the patent shall cover by suitable expression in the appended claims whatever features of patentable novelty exist in the improvements disclosed.

In the accompanying drawings:

Fig. 1 is a vertical medial section of a barrel embodying one form of my improvements;

Fig. 2 is a similar section showing another form of my improvements;

Fig. 3 is a perspective of a detail; and

Fig. 4 is a somewhat diagrammatic showing of how my improvements may be applied.

My improvements can be incorporated in either an insulated barrel or one that is not insulated. I have therefore shown both types of barrel in the drawings but it is to be understood that although I have shown the more simple arrangement of the cooling and delivery passages in an uninsulated barrel (Fig. 2) this arrangement can likewise be incorporated in an insulated barrel.

The form of barrel shown in Fig. 1 comprises 25 an inner shell 10 which contains the liquid to be dispensed. This shell has a head 12 and a bottom 14 preferably welded to its side wall. Outside of this inner shell is an intermediate shell 16 so arranged as to provide a helical flow passage 30 for cooling liquid. The side wall of this intermediate shell is formed with a rather large helical corrugation 18 whose inner edge 20 makes a nice sliding fit with the external wall of the inner shell 10. At both the bottom and top, the heads 16a and 16b of the intermediate shell are for the most part spaced from the inner shell to permit the cooling liquid to bathe the heads of the inner shell. Outside the intermediate shell 16 is an outer shell 22 whose side wall can be slipped along the outer edges of the corrugation 18 of the intermediate shell. This outer shell has heads 24 and 26 welded to its side wall.

The helical corrugation 18 of the intermediate shell provides two helically shaped spaces 28, 30 along the side of the barrel. The inner space 28 serves as a passageway for the cooling liquid while the outer space 30 is preferably packed with insulating material 32. My improved delivery pipe 34 is shown nested in the inner helical space 28 through which the cooling liquid flows.

50

The entrance to the delivery pipe is a bent piece of piping 36 that is secured to the bottom head 14 of the inner shell 10. This bent piece of piping is connected to the delivery pipe and thus the beverage is received into the latter at the bottom of the barrel. The delivery end 34a of the pipe 34 is at the top of the barrel and is preferably provided with a so-called "Golden Gate" fitting 38. At the top end of the barrel is a short piece of pipe 40 which projects somewhat within the inner shell 10 and is also provided with a "Golden Gate" fitting 42. This pipe 40 is connected with a source of pressure when the beverage is to be discharged. The barrel may be initially filled through this pipe 40 or through a pipe 41 in the side of the barrel. This latter pipe is normally closed by a bung 43.

In constructing the form of barrel shown in the drawings, the bent piece of piping 36 is secured to the bottom head 14 of the inner shell and then this head is welded to the side wall of the same shell. Similarly the pipe 40 is secured to the head 12 of the shell 10 and then this head is welded to the side wall. A hole 45 is drilled in the side wall and tapped so that later the pipe 41 can be screwed into it.

The side wall of the intermediate shell 16, near its ends, is drilled and tapped at 44 and 46 and "Golden Gate" fittings 48 and 50 are inserted. Another hole 47 is drilled in the wall of the intermediate shell so as to register with the hole 45, the latter being somewhat smaller than the hole 47. For the moment a plug (not shown in the drawings) somewhat shorter than the space between the intermediate shell and the outer shell is lightly screwed into the hole 45 so that the insulation 32 can be applied without entering the inner shell.

The delivery pipe 34 (which is preferably made of bendable metal) is nested within the inner helical space 28 formed by the helical corrugation 18 of the side wall of the intermediate shell 16. This shell and the delivery pipe nested therein are slipped over the inner shell 10 and the end 34b of the delivery pipe is secured to the bent piece of piping 36. The lower head 16a of the intermediate shell is then welded to its shell, after which the upper head 16b is also secured, there being suitable holes in this upper head to permit the pipe 40 and the end 34a of the delivery pipe to project outside the head. Both the pipe 34 and the pipe 40 are welded to the head 16b of the intermediate shell to prevent any leakage later of the cooling liquid. The insulation 32 is now applied to the helical space 30 about the intermediate shell.

The outer shell is provided with holes 52 and 54 arranged to register with the "Golden Gate" fittings 48 and 50 respectively of the intermediate shell. When the barrel is not connected for circulation of cooling liquid, these holes 52 and 54 are closed by removable plugs 56 and 58 respectively. Another hole 55 is also provided in the outer shell so as to come opposite the holes 45 and 47 in the other two shells. This hole 55 is slightly larger than the pipe 41.

The lower head 26 is secured to the shell 22 and after the insulation material has been placed against this head, the intermediate shell 16, delivery pipe 34, and insulation packing 32 are slipped into the shell 22. The upper head 24, which has holes to accommodate the pipe 40 and the end 34a of the delivery pipe, is put in place and welded to the wall of the outer shell 22. This head 24 may be secured to the pipes 34 and 40 by

nuts 56 and 58 respectively or welded joints may be made between the head and the pipes. The "Golden Gate" fittings 38 and 42 are then applied to the ends of the pipes 34 and 40. The plug (hereinbefore mentioned but not shown) is then removed from hole 45 through the hole 55 and the pipe 41 inserted. This has a threaded inner end which screws into the tapped hole 45 in the inner shell 10 and has a shoulder at the ends of its threads which overlies the edge of hole 47 in the intermediate shell 16. Accordingly, upon the pipe 41 being screwed in firmly, the intermediate shell is clamped tightly to the inner shell. The outer edge of the pipe 41 is finally welded to the outer shell 22. By this construction it is clear that the inner shell is tight for holding the liquid to be delivered and the intermediate shell is also tight to carry the flow of a cooling medium.

If the barrel is filled through the pipe 41, it is desirable, after the bung 43 has been driven in tight, to place the barrel upright, as shown in Fig. 1, and with the fitting 38 open apply a slight pressure through the fitting 42 and pipe 40 to insure that the delivery pipe 34 is also filled with the beverage. It is also desirable to fill the space 28 between the inner shell and intermediate with a cold liquid to keep the beverage cool during transit. While waiting to be used, the filled barrel should be connected to a source of cooling liquid which will flow continuously through the space 28 between the inner and intermediate shells. It is intended that a number of such barrels will be held in storage and that all will be connected with the supply of cooling medium so that the latter will flow continuously through all the barrels. This, in effect, amounts to keeping the beverage in "sold storage" until it is dispensed.

When the beverage in the barrel is to be dispensed a suitable conduit leading to a dispensing faucet is connected with the fitting 38 on the end 34a of the delivery pipe and the fitting 42 on the pipe 40 is connected with a source of pressure supply. If the preferred "Golden Gate" fittings are used, these connections can be made without loss of any of the beverage and, what is more important in the case of a charged liquid, without disturbing its carbonated condition.

When the dispensing faucet is opened, the beverage is forced into the bent pipe 36 and caused to flow through the coiled length of the delivery pipe 34 to the outlet end 34a connected with the faucet. Since the pipe 34 is nested in the space traversed by the cooling medium, the beverage taken from the inner shell is given its maximum chill as it flows through the delivery pipe 34 and thus reaches the faucet at a temperature which insures its discharge as a liquid, without foaming or frothing, and still in its desired carbonated condition. This is an important feature where the beverage is a charged liquid, because unless the temperature of such a liquid is maintained below a certain degree, the carbonated condition of the liquid is reduced and may be so depleted as to spoil the beverage. And with beer and ale, not generally deemed to be carbonated liquids, it is highly desirable to keep the temperature low and to give the final maximum chill to the beverage as it is being withdrawn from the barrel.

Referring now to Figs. 2 and 3, I have shown in these figures a more simple embodiment of my invention. In this form the principles of my invention can be incorporated in any barrel whether it is insulated or not. For purposes of illustration, I have shown a simple metal barrel but the

features of my invention could be used in a wooden barrel as well.

The barrel of Fig. 2 has a shell 60 made in two half sections 62 and 64 which can be welded together around their overlapping edges, 66 and 68. At one side of the barrel, preferably midway thereof, is a hole 70 through which the beverage may be inserted into the barrel and which is normally closed by a bung 72. Near the bottom of the barrel on the side thereof in a recessed portion 74 of the shell is a hole 76 through which a pipe 78 extends and has at its outer end a so-called "Golden Gate" fitting 80. The inner end of this pipe 78 is somewhat enlarged and has a slot 82 to permit the pipe 78 to slip over the end of another pipe 84 also slotted on one side.

The pipe 84 coils around inside the barrel and within it is a smaller pipe 86, preferably held in concentric relation to the outer pipe 84 by a piece of wire 88 helically disposed between the two pipes. This wire not only serves as a spacer between the two pipes 84 and 86 but also causes the cooling liquid to flow helically between these pipes, thus providing additional opportunity for the cooling liquid to absorb heat both from the beverage in the pipe 86 and from the beverage in the barrel outside the pipe 84. At the bottom the internal pipe 86 turns outward through the opening formed by the slots in the pipes 78 and 84. When arranged together as seen in Fig. 2, the two pipes 78 and 84 are welded together and also to the pipe 86. At the top of the barrel, the inner pipe 86 extends directly through the barrel head 90 and terminates in another "Golden Gate" fitting 92. Just above the barrel head, the outer pipe 84 is closed tight above an offset portion 86a which extends outward and upward and has at its end still another "Golden Gate" fitting 94. In the head of the barrel is a third pipe 96, with a "Golden Gate" fitting 98. This pipe barely extends within the barrel.

When the barrel is being stored, a source of cooling fluid is connected with the "Golden Gate" fitting 94, and a return to the same source may be connected to the "Golden Gate" fitting 80 at the bottom of the barrel, or the latter fitting may be connected to a waste pipe. Cooling liquid is forced to flow through the outer pipe 84 between it and the inner pipe 86 and during its flow absorbs heat from the beverage stored in the barrel.

When the beverage is to be withdrawn from the barrel, like connections are made with the fittings 89 and 94 for the continuous flow of a cooling fluid. In addition, a source of pressure is connected to the fitting 98 and the fitting 92 is connected with a dispensing faucet. When this faucet is opened for discharge of the beverage, the latter enters the inner pipe 86 through the open end at the bottom, passes upward through the inner pipe in counter-flow relation to the cooling liquid flowing between the two pipes 84 and 86, and leaves the barrel at its top, passing through the fitting 92 on its way to the faucet.

While flowing through the inner pipe 86, the beverage is given the maximum cooling effect, thus reducing its temperatures to a degree which keeps the beverage in a truly liquid state for discharge from the faucet. No foaming or frothing occurs and, in the case of charged liquids like ginger ale, soda water, and the like, this final cooling prevents any loss of carbonation and insures that the charged liquid will be delivered in its proper condition as a liquid instead of a gas or a mixture of gas and liquid.

This provision for the final cooling of the bever-

age as it flows along the inner pipe enables charged liquids to be sold in barrels instead of in bottles as is now customary. The general cooling of the beverage by the cooling fluid flowing between the coiled pipes keeps the beverage at such a temperature that it prevents the loss of carbonation from a charged liquid, and in the case of beer, ale or the like, prevents any re-fermentation thereof. And the final maximum cooling of the beverage as it flows along the inner pipe, so additionally chills the beverage that it flows on to the dispensing faucet in the desired purely liquid state.

While it is intended that the barrel embodying my improvements shall be placed under a counter in close proximity to the dispensing faucet, it is nevertheless contemplated that the barrel may be located in a basement or on some floor level below that on which is the counter. When this is necessary, the arrangement shown in Fig. 4 is preferable.

In this arrangement the fitting 98 of the barrel is connected to a source of pressure 100. The fitting 92, through which the beverage leaves the barrel, is connected by a pipe 102 to another inner pipe 104 arranged within an outer pipe 106. The inner pipe 104 extends to a dispensing faucet 108 on a counter 110. The outer pipe 106 continues outside the inner pipe 104 to close by the faucet just under the counter top. The upper end of this outer pipe 106 is connected by a pipe 112 to a source 114 of cooling fluid, which is also connected by a pipe 116 to the fitting 80 near the bottom of the barrel. The lower end of the outer pipe 106 is connected by a pipe 118 with the fitting 94 of the barrel. Thus it is clear that the cooling fluid from source 114 flows to the upper end of pipe 112, thence through this pipe around the inner pipe 104 to the upper end of the outer pipe 84 within the barrel. Thence the cooling liquid flows as previously described between the pipes 84 and 86 to the fitting 80 whence it returns by pipe 116 to the source 114.

Although in Fig. 4 I have only shown one barrel it is contemplated that several barrels may be at the lower level with separate delivery pipes leading to several faucets on the counter. All these several delivery pipes may be embraced by one common outer pipe containing the cooling fluid, which shall extend from close by the several barrels to the several faucets. It is to be understood also that I may have a multi-chambered barrel or container, each chamber holding a different fluid such as ginger ale, a cola drink, soda water, etc. From each chamber a delivery pipe would lead through a common conduit in which a cooling fluid would be continuously circulated preferably in a direction of flow counter to that of the liquids going to the dispensing faucets.

I claim:

1. A barrel for beverages comprising a pipe coiled therein having an entrance end at the top of the barrel and having an outlet end near the bottom of the barrel, and a second pipe arranged within the first said pipe having its entrance end near the bottom of the barrel and having its outlet at the top of the barrel; the second pipe constituting a delivery passageway for the discharge of beverage from the barrel and the space between the two pipes constituting a passageway for the flow of a cooling fluid.

2. Beverage dispensing apparatus comprising a barrel having a pipe therein for the flow of cooling fluid and a second pipe within the first

mentioned pipe for the flow of the beverage from within the barrel, the said beverage pipe being connected by a third pipe to a dispensing faucet outside of and separate from the barrel, and the said cooling fluid pipe being connected to a manifold pipe surrounding the said third pipe, through which manifold pipe the cooling fluid may flow from its source to the first mentioned pipe within the barrel and thence through the barrel to an outlet for the cooling fluid near the bottom of 10 the barrel.
